WEFT STOP MOTION FOR NARROW WARE LOOMS

Filed May 8, 1943

FIG. 2

UNITED STATES PATENT OFFICE

2,356,458

WEFT STOP MOTION FOR NARROW WARE LOOMS

Elbridge R. Holmes, Worcester, Mass., assignor to
Crompton & Knowles Loom Works, Worcester,
Mass., a corporation of Massachusetts

Application May 8, 1943, Serial No. 486,238

13 Claims. (Cl. 139—371)

This invention relates to improvements in narrow ware looms and it is the general object of the invention to provide improved means for stopping the loom, or effecting a change in the loom, should the weft in a shuttle be broken or exhausted.

Narrow ware looms operate with a bank of shuttles which are moved back and forth through relatively narrow sheds by rack and pinion mechanism. The weft is wound on quills extending lengthwise of the shuttle and tensioning mechanisms mounted on the shuttle provide an angular path which the weft traverses from the quill to the delivery eye of the shuttle. Because of the nature of the weft system within the shuttle it has not been practical in the past to determine weft breakage or exhaustion. It is an important object of my present invention to mount a detector on the shuttle and locate it within the overall outline of the shuttle so that it will not interfere with the warp threads when the shuttle is passing through the shed, and construct the detector so that upon weft fault it will fall to an indicating position outside the overall outline of the shuttle and cooperate with means to bring about a change in actuator loom operation, such as stoppage.

Due to the forward movement of the lay which carries the shuttles any moving detector in the shuttle should be so constructed that it will not be materially effected by momentum as the lay advances. It is accordingly a further object of my present invention to mount the detector so that it moves around a pivot which is substantially parallel to the direction in which the shuttle advances as the lay beats up.

The aforesaid guide mechanism for the weft within the shuttle generally includes a pair of eyes through which the weft is threaded. These eyes, together with the delivery eye of the shuttle and a third eye, determine the weft path when the thread is taut. It is another object of my present invention to mount the detector in such a position in the shuttle that it will be located below that portion of the thread path extending between the aforesaid guide eyes and not interfere with the thread.

It is a further object of my present invention to provide the loom with a form of electric switch which is closed during advance movement of the lay when the detector has fallen to indicating position due to weft failure. This feature of my invention may include a resiliently mounted plunger normally extending under the shuttle at front center and below the detector when the

thread is intact but positioned to be engaged by the detector upon weft failure. The plunger is then moved forwardly to close an electric switch in circuit with loom stopping mechanism.

With these and other objects in view which will appear as the description proceeds, my invention resides in the combination and arrangement of parts hereinafter described and set forth.

10 In the accompanying drawing, wherein a convenient embodiment of my invention is set forth,

Fig. 1 is a front elevation of a portion of the lay and breast beam of a narrow ware loom showing my invention,

15 Fig. 2 is an enlarged plan view looking in the direction of arrow 2, Fig. 1, with the mechanism in non-indicating position,

Fig. 3 is an enlarged section on line 3—3 of Fig. 2 showing the shuttle detector in non-indicating position in full lines and in indicating position in dotted lines,

Fig. 4 is an enlarged detailed section on line 4—4 of Fig. 2,

20 Fig. 5 is a diagrammatic view of one type of control electric circuit which can be used with my invention, and

Fig. 6 is an enlarged transverse section on line 6—6 of Fig. 2.

Referring particularly to Figs. 1 and 2, I have shown a lay 10 of a narrow ware loom provided with shuttle blocks 11 and 12 which alternate with the reed spaces 13. In the present instance each shuttle block is provided with intersecting arcuate grooves or slots 14 to receive curved or arcuate bow shuttles S. As shown in Fig. 2 each shuttle has a body 15 through which passes a vertical opening or slot 16 across which extends a shuttle pin or spindle 17. The quill 18 carrying the weft supply W is mounted on the pin 17 and is engaged by a friction pad 19 of the usual type. Mounted at the sides of the opening 16 are right and left hand guide eyes 20 and 21, respectively, while the front or bowed wall 22 of the shuttle is provided with a third guide eye 23 and a weft delivery eye 24. The weft will ordinarily follow the path indicated in Fig. 2, leading forwardly from the quill 18 to the central eye 23, then to one of the side eyes, as 20, then

40 across the space 16 to the other eye 21, and thence to and out of the delivery eye 24. It is customary to mount the guide eyes 20 and 21 on springs not shown which are embedded in the body of the shuttle. Mechanism including pinions 30 and a rack 31 cause the shuttles to swing back

45 50 55

and forth from one shuttle block to the other across the intervening reed space.

The loom may operate with any approved form of control or indicating mechanism, but in Fig. 5 I have shown means for stopping the loom on operation of my invention. This means includes a shaft 35 which rotates during loom operation and has a cam 36 to rock a lever 37 mounted on a fixed pivot 38. A knock-off lever 39 movable above a fixed pivot 40 is connected to a rod 41 extending to the loom shipper mechanism not shown and also has pivoted thereto a link 42. A normally deenergized solenoid 43 has a core 44 operatively connected to the link 42, and a weighted positioner 45 is pivoted under the link 42.

Arm 46 of lever 37 has a working stroke to the right as viewed in Fig. 5 for each rotation of cam 36. Arm 46 is undercut as at 47 so that it passes over the left end of link 42 when the latter is in its normal down position shown in dotted lines in Fig. 5.

Normally the weight 45 is diagonal to permit the lever 42 to lie out of the path of the arm 46, but when the solenoid 43 is energized its core 44 is raised to elevate the link 42 into the path of arm 46. The weight positioner 45 then swings to the full line position shown in Fig. 5 to hold the link temporarily in raised position. On the next working stroke of arm 46 the link is moved to the right to rock the knock-off lever 39 and rod 41 to the right to operate the shipper mechanism and stop the loom.

The knock-off mechanism and control therefor shown in Fig. 5 is illustrated as one way in which my invention may be utilized and for further description of its structure and operation reference may be had to Payne Patent No. 1,873,465.

Except as noted hereinafter the matter thus far described is of common construction and may be made in the usual manner. If desired the shuttle blocks can have horizontal slots and the shuttles made straight so that they pass from one block to the other in a path parallel to the lay. This form of shuttle and shuttle block is very common and I have not illustrated it herein but wish it to be understood that my invention is not limited to the use of arcuate shuttles.

Referring more particularly to Figs. 2 and 3, it will be seen that I have provided the inside forward walls of the shuttle with right and left hand supports 50 and 51, respectively, to which right and left hand detector links 52 and 53 are pivoted as at 54. Stops 55 carried by the forward shuttle wall overhang the links and limit their upward movements as indicated more particularly in Fig. 3 to keep the links below the weft path previously described. The right hand link 52 is provided with a longitudinal slot 60 which receives a pin 61 secured to the left link 53. The adjacent jointed ends of the links are rounded as indicated in Fig. 3 and the pin and slot connection between them requires that they move together angularly.

The breast beam 65 of the loom carries a stand 66 provided with a rearwardly extending support 67 held to the stand by a bolt 68 passing through a slot 69 in the support to permit back and forth adjustment of the support with respect to the breast beam and the sweep of the lay. As shown in Fig. 4 the rear part of the support 67 is provided with a bore 70 in which is slidably mounted a plunger 71 the front end of which is provided with a stem 72 slidable on the support 67 and surrounded by a light compres-

sion spring 73 located in the forward part of the bore 70. The rear part of the plunger 71 extends beyond the rear end of the support 67 and is provided with an electric conducting ferrule 75 held to the plunger in any approved manner, as by prongs 76. A pin 77, see Figs. 2 and 6, secured to plunger 71 extends through slot 78 in the support 67 to guide and limit rear motion of the plunger relatively to the support. Both the plunger and the support 67 are made preferably of electric insulating material such as fiber so that the ferrule 75 is insulated from the support. The right and left rear sides of the support 67 are provided with electric spring contacts 80 and 81, respectively, held to the support by screws 82. Contact 80 connects electrically with a wire 83 while the other contact 81 is connected electrically with wire 84.

The support 67 is held in such position on the stand 66 that the plunger is below the shuttle path and the spring 73 ordinarily holds the plunger rearwardly with the ferrule 75 located behind and out of contact with the spring contacts 80 and 81. If desired, the spring contacts can be made strong enough to hold the plunger 71 forwardly by frictional engagement with ferrule 75 against the action of coil spring 73, in which case rearward movement of the plunger to normal position subsequent to forward motion is effected manually.

In operation, the weft extends forwardly from the quill 18 under the jointed links and then passes through the control or intermediate guide eye 23. The tension of the weft is sufficient to maintain the jointed links in the full line position shown in Fig. 3 and as the lay beats up it passes over the plunger 71 without moving the latter. As the weft unwinds from the quill it slides back and forth under the links 52 and 53 and their rounded jointed ends. If the weft in the shuttle should break or become slack the detector links 52 or 53, being unsupported by the weft, will fall by gravity to the dotted line position shown in Fig. 3 and on the next forward movement of the shuttle the detector links will engage the rear end of the plunger 71 as will be understood from reference to Fig. 3 and move the plunger forwardly to locate the ferrule 75 between and in engagement with the contacts 80 and 81 to close the circuit indicated in Fig. 5. The pivots 54 are so constructed as to support the links against the rearward thrust of plunger 71.

The circuit comprises a source of electric power E one side of which is grounded by wires 90 and the other side of which is connected to the wire 84. Wire 83 is connected to one side of the solenoid 43 and the other side of the latter is connected by wire 91 to the ground. Closure of this circuit by forward movement of the ferrule 75 to indicating position as shown in Fig. 5 causes energization of the solenoid 43 with resultant upward movement of the link 42 in the path of arm 46 to effect loom stoppage as already described. When the weaver corrects the defect in the weft, either by replacing an exhausted quill 18 or reestablishing normal weft tension, the forwardly extending strand of the weft will again lift the detector links 52 and 53 to their normal non-indicating full line position shown in Fig. 3.

The cam 36 can if desired rotate every second pick of the loom to move lever arm 46 to the right shortly after the lay reaches front center on alternate beats when the shuttle is on block 11. The operation of the invention is not limit-

ed to this specific timing, however, and as previously mentioned the shuttles need not necessarily move in the curved path suggested in Fig. 1. When contact springs 80 and 81 are strong enough to hold the plunger 71 in rear position, manual resetting subsequent to loom stoppage will be necessary. The advantage of holding plunger 71 forwardly by spring contacts 80 and 81 after the lay leaves front center is to permit any electric circuit which may be used to remain closed independently of the lay position. I am not limited to the relation mentioned between the strengths of spring 73 and the contacts 80 and 81, however, and spring 73 can be made strong enough to return the plunger 71 to normal rear position automatically as the lay recedes.

It will be seen from Fig. 2 that certain parts of the weft in the shuttle cross the vertical plane in which the links 52 and 53 swing, and it will further be noted that the part of the weft extending between the eyes 20 and 21 is more or less parallel to the links. In Fig. 2, this last named part of the weft is shown as spaced a relatively large distance from the detector links for the sake of clarity, but in actual practice, with certain types of shuttles at least, this part of the thread will lie close to the parallel links. The stops 55 prevent any possible interference between the weft when it is under normal tension and the detector links 52 and 53, and the latter are kept below the plane in which lies that part of the weft extending between the eyes. Because of this relationship there is little or no danger that the weft will be entangled with the jointed ends of the detector links.

As the lay advances the links 52 and 53 tend by their momentum to move forwardly, and unless the links were correctly pivoted they might swing to a position above the plunger 71. By referring to Figs. 2 and 3 it will be seen that the link pivots have their axes disposed more or less parallel to the direction of advance of the lay and the links therefore fall to and remain in proper indicating position without interference by their momentum.

From the foregoing it will be seen that I have provided a simple form of control for narrow ware looms wherein the shuttle is provided with a detector element normally held raised by the weft when the latter is under proper tension. When weft tension fails, as by exhaustion of the quill or undue slackness, the links 52 and 53 fall from their normal to indicating position so that forward movement of the shuttle with the lay can establish contact between the ferrule 75 and the spring contacts 80 and 81. It will be noted that the detector links move in a plane which is transverse of the direction in which the shuttle advances and are held by their pivots against objectionable forward displacement due to their momentum as the lay advances. Furthermore, the detector link pivots and their stops are so located as to maintain the detecting mechanism below the plane normally occupied by the weft when the latter is under proper tension. Also, the link pivots 54 are so disposed that the links never strike the quill to injure its weft.

Having thus described my invention it will be seen that changes and modifications may be made therein by those skilled in the art without departing from the spirit and scope of the invention and I do not wish to be limited to the details herein disclosed, but what I claim is:

1. In a weft stop mechanism for a narrow ware

loom having a reciprocating lay, a shuttle on the lay having a weft quill, a detector in the shuttle normally supported by the weft when the latter is under proper tension and falling to an indicating position when unsupported by the weft, a normally open electric switch on the loom, means operated by the detector when the latter is in indicating position during forward movement of the lay to close said switch, said switch constructed to hold the means in position to maintain the switch closed during backward movement of the lay, and an electric control circuit for the loom closed when said switch is closed.

2. In a weft stop mechanism for a narrow ware loom having a reciprocating lay and a frame, a detector in the shuttle held in normal position by the weft when the latter is under normal tension and moving to indicating position below the normal position thereof when unsupported by the weft, a plunger for cooperation with the indicator, means to mount the plunger on the loom frame for forward motion below the shuttle and in the path traversed by the indicator when the latter is in indicating position during forward movement of the lay, and electrically controlled means for the loom including a normally open electric switch closed by the plunger when the latter is moved forwardly by the indicator in indicating position as the lay advances.

3. In a weft stop mechanism for a narrow ware loom having a reciprocating lay and a frame, a detector in the shuttle held in normal raised position by the weft when the latter is under proper tension and moving to an indicating position below the normal position thereof when unsupported by the weft, a normally open electric switch mounted on the loom frame, normally open electric circuit control means for the loom closable by the switch to effect a change in loom operation, and a switch closer below the advancing path of the detector when the latter is in normal position but in position to be actuated by the detector when the latter is in indicating position during advance movement of the lay to close said switch.

4. In weft stopping mechanism for a narrow ware loom having a shuttle on a reciprocating lay, loom controller means including a part forward of the shuttle and normally in non-controlling position but movable forwardly to controlling position, a detector within the shuttle supported in normal raised position by the weft when the latter is under proper tension and moving pivotally to indicating position when unsupported by weft, and a pivotal support for the detector carried by the shuttle and having an axis which is substantially parallel to the back and forth motion of the lay, to the end that the detector moves pivotally from normal to indicating position about the pivotal support thereof independently of momentum of the detector due to forward movement thereof with the shuttle.

5. In a narrow ware loom having a backwardly and forwardly reciprocating lay provided with a shuttle, a loom controller normally in non-controlling position but movable to controlling position, a pair of spaced parallel pivots on the shuttle the axes of which are parallel to the back and forth motion of the lay, a link mounted for angular movement on each pivot, and means to connect the ends of the links remote from their pivots, the weft when under proper tension effective to hold said links in raised normal posi-

tion and said links when unsupported by the weft falling about their pivots to an indicating position for engagement with the controller to move the latter to controlling position by a force derived from the lay as the latter moves forwardly.

6. In a narrow ware loom having a horizontally reciprocating lay provided with a shuttle having a weft quill rotatably mounted thereon, weft guides carried by the shuttle through which the weft from the shuttle passes, said guides causing the weft extending between them to maintain a given level when the weft is under proper tension, a weft detector movably mounted on the shuttle normally supported in non-indicating position by the weft when the latter is under proper tension and moving to indicating position when unsupported by the weft, means to prevent said detector from moving upwardly to said level, and control means for the loom set in operation during forward movement of the lay when the detector is in indicating position.

7. In a narrow ware loom having a horizontally reciprocating lay provided with a shuttle carrying a rotatable weft quill, weft guides on the shuttle through which the weft from the quill passes, said guides maintaining weft when the latter is under proper tension at a given elevation in front of the quill, a detector pivoted to the shuttle and movable in a plane crossing said given level, stop means for the detector cooperating with the weft when the latter is under proper tension to maintain the detector in non-indicating position below said given level, said detector when unsupported by the weft moving to indicating position, and means set in operation by the detector when the latter is in indicating position during forward movement of the lay to control the loom.

8. In a narrow ware loom having a horizontally reciprocating lay provided with a shuttle carrying a rotatable weft quill, guide means on the shuttle causing the weft when the latter is under proper tension to traverse a given path between said guides, a weft detector in the shuttle movable in a plane toward and from said path, means carried by the shuttle cooperating with the weft when the latter is under proper tension to maintain said detector in normal position below said path, said detector when unsupported by the weft falling to indicating position, and means set in motion by the detector when the latter is in indicating position during forward movement of the lay to control the loom.

9. In a narrow ware loom having a horizontally reciprocating lay provided with a shuttle carrying a rotatable weft quill, guide eyes car-

ried by the shuttle to receive the weft from the quill and cause the weft when under proper tension to traverse a given path, weft detector mechanism in the shuttle including two jointed links pivoted on the shuttle and movable toward and from said given path, said links supported in non-indicating position by a strand of the weft leading from the quill from one of said guide eyes when the weft is under normal tension, said detecting mechanism moving to indicating position when unsupported by the weft, stop means carried by the shuttle to prevent movement of said jointed links to said given path, and means set in motion by the detector when in indicating position during forward movement of the lay to effect a change in the operation of the loom.

10. In a narrow ware loom shuttle having a body and a weft quill rotatably mounted in a weft chamber in the body, weft guide eyes supported by the body and defining a path for weft drawn from the quill, a weft detector pivotally mounted on the body and movable in a plane crossing said path, and means to confine the pivotal movement of the detector to a zone below said path.

11. In a narrow ware loom shuttle having a body and a weft quill rotatably mounted in a weft chamber in the body, a pair of jointed weft detector links extending in the direction of the length of said quill, and pivotal supports on said body for the remote ends of said links extending transversely of said quill and requiring the links to move in a plane spaced from said quill.

12. In a narrow ware loom shuttle having a body and a weft quill rotatably mounted in a weft chamber in the body, a weft guide eye on said body, and weft detector mechanism mounted on the shuttle body between said quill and said eye and supported by a weft extending from the quill to the eye, said mechanism comprising jointed links and pivots for the remote ends of said links extending in such a direction as to cause the links to move angularly in a plane between said eye and said quill.

13. In a narrow ware loom shuttle having a body and a weft quill rotatably mounted in a weft chamber in the body, a weft guide eye on said body, and weft detector mechanism mounted on the shuttle body between said quill and said eye and supported by a weft extending from the quill to the eye, said mechanism comprising a pair of parallel pivotal supports, one on each side of said chamber, a detector link pivoted to each support and extending toward the other support in a direction substantially parallel to said quill, and means joining the adjacent ends of said links.

ELBRIDGE R. HOLMES.
